UNITED STATES PATENT OFFICE.

MARSHALL B. LLOYD, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

REED-WEAVING MACHINE.

Application filed September 14, 1925. Serial No. 56,139.

This invention relates to improvements in reed weaving machines and consists of the matters hereinafter described and more particularly pointed out in the appended claims.

- 5 One of the objects of the present invention is to provide a machine capable of producing a flat reed fabric and to incorporate therein at the desired intervals, a pattern, design or other character.
- 10 Another object of the invention is to provide an improved pattern controlling means, which actuates the shed forming devices in such a manner that adjacent filler strands are simultaneously moved together so that
- 15 upon insertion of a stake, into the shed, said adjacent strands will be located on one side of said stake and upon the other side of adjacent stakes so as to form patterns or designs contrasting from the body of the fabric wherein each strand passes over and under the stakes.

20 My invention consists generally in a machine of the form, arrangement, construction and co-operation of the parts, whereby the above mentioned objects, together with others, are attainable; and my invention will be more readily understood by reference to the accompanying drawings which illustrate what I consider at the present time to be the preferred embodiment thereof.

In the drawings:

Fig. 1 is a view in top plan elevation of a reed weaving machine embodying my invention.

35 Fig. 2 is a longitudinal vertical sectional view through the same as taken on the line 2-2 of Fig. 1.

40 Fig. 3 is a detail transverse vertical sectional view on an enlarged scale as taken on the line 3-3 of Fig. 2.

Fig. 4 is a detail view on an enlarged scale of parts shown at the left hand side of Fig. 2.

45 Fig. 5 is a view similar to Fig. 4 but with several of the parts in a changed relation.

Fig. 6 is a perspective view of one of the members embodied in the means for manipulating or shifting portions of the filler strands to form the shed.

50 Fig. 7 is a perspective view of another member associated with the member shown in Fig. 6 for forming the shed.

Fig. 8 is a view in elevation of that side of the machine shown at the right hand end 55 of Fig. 1.

Fig. 9 is a view showing a design or pattern incorporated in the flat fabric produced by my improved machine.

Fig. 10 is a detail vertical sectional view on an enlarged scale as taken on the line 10-10 of Fig. 1.

Fig. 11 is a perspective view of a portion of one of the pattern control cylinders or drums and will be more particularly referred to later.

Fig. 12 is a detail view in elevation on an enlarged scale of parts shown in Fig. 1 and as looked at in the direction of the arrows, associated with the line 12-12 thereon.

Fig. 13 is a vertical detail sectional view 70 as taken on the line 13-13 of Fig. 12.

Fig. 14 is a horizontal detail sectional view as taken on the line 14-14 of Fig. 12.

Cross reference is made to my copending application filed August 29, 1925, Serial No. 53,281, wherein similar subject matter is disclosed but not claimed therein.

Generally speaking, in the machine shown herein the filler strands are arranged in side by side contact and pass in this relation 80 through means which engage successive portions of alternate and intermediate strands and depress and elevate said portions in opposition to form a shed. Said means are actuated and controlled by what may be termed "pattern cylinders" the peripheral contour of each of which has parts so arranged that during a part of the rotation of the cylinders, groups of alternate strands are depressed out of their normal plane 90 while groups of intermediate strands are elevated out of their normal plane to form a shed into which the stakes are inserted and at other times groups of adjacent alternate and intermediate strands are brought into 95 the same plane to form the sheds into which said stakes are inserted. A magazine is provided to hold a number of stakes and a gripper device removes the stakes from the magazine one at a time and presents them 100 to a means which inserts them into the sheds as they are formed. Should the stakes be bent out of their true straight condition they are straightened after insertion into the sheds. Thereafter the fabric passes between 105 coacting rolls having longitudinally extending, angular corrugations that accurately form and somewhat compress the strands upon the stakes after which the finished fabric is wound upon a roll or mandrel.

110

Referring now in detail to that embodiment of the invention illustrated in the accompanying drawings:—the machine includes upright spaced side plates or frames 1 and 2 of suitable form. Said side plates are held in the desired spaced relation by means of a front plate 3 and a rear tie rod 4, and if desired other members may be employed between said front plate and tie rod 10 to assist the same in a manner most apparent. Each side plate or frame includes at its forward top end, a short upright extension 5 and rising from each side frame at the ends of said extensions are pairs of front 15 and rear standards 6—6. The top end of each pair of standards is connected together by a bridge block 7 and said extension 5, standards 6 and bridge block 7 define a rectangular opening 8, all as best shown in 20 Fig. 2.

Fixed to the rear sides of the front standards 6—6 on said side frame members 1 and 2, in the horizontal median plane of the openings 8—8 is a vertically edgewise disposed plate 9. Said plate is provided with a plurality of openings 10—10 through which filler strands 11—11 pass from associated supply spools (not shown). Said openings are so disposed as to bring said strands in closely adjacent vertical planes and so as to prevent the abrasion or wear on said strands, the entrance ends of said openings are flared outwardly. Journalled in the side frame members 1 and 2 near their rear ends is a transversely extending horizontal shaft 12 which is the main drive shaft of the machine and from which the associated mechanisms are driven as will later appear.

13 and 14 indicate respectively top and bottom cross bars which are fixed at their ends to the bottoms of the bridge blocks 7—7 and to the tops of the extensions 5—5 respectively, near the rearmost standards 6—6 on said side frame members. Each cross bar includes a front vertically disposed flange 15 in the front face of which are provided, longitudinally spaced vertically extending grooves 16. Associated with said bars 13 and 14 but spaced forwardly therefrom are similar top and bottom cross bars 17 and 18, respectively, which are also fixed at their ends to said bridge blocks and extensions as best shown in Figs. 2 and 4. The front cross bars 17 and 18 each include a horizontal flange 19 and a rear vertical flange 20, said horizontal flanges being spaced a short distance away from the associated frame extensions 5 and bridge blocks 7 by suitable washers or the like as best shown in Fig. 2, said vertical flanges facing in opposition to the vertical flanges of the other cross bars 13 and 14. Secured to the top of the cross bar 17 and to the bottom of the cross bar 18 are top

and bottom members 21 which overhang and project rearwardly beyond the plane of the vertical flanges 20 of said cross bars and in said members 21—21 are longitudinally spaced opposed openings 22, the purpose of 70 which will appear later.

Associated with the top cross bar 13 is a plurality of filler strand manipulating members 23, one of which is best shown in perspective in Fig. 6. Each member 23 is 75 of L shaped form and includes an elongated upright body 24, the top end of which is bifurcated to provide laterally spaced ears 24^a—24^a. The bottom end of said body has a substantially right angular extension 80 and in said extension and extending a part way up the body portion are grooves or recesses 25 which define spaced plate like parts 26. The grooves and plate-like parts are so disposed as to provide a plate-like 85 part on one side of said member and a groove-like part on the other side thereof. The bottom edges 27 of said plate like parts are finished off on an angle less than a right angle and are inclined upwardly from the rear side of the body toward the end of the extension and on the rear side of said body midway between its ends is formed a tongue or rib 24^b which has sliding guiding bearing in one of the grooves 16 in the cross bar 90 13. Mounted on the bottom cross bar 14 is another plurality of filler strand manipulating members 27 which occupy a position reversed end for end with respect to those on the cross bar 13. As said members are identical with those just described it is not thought necessary to again describe them in detail.

Associated with the cross bars 17 and 18 are strand manipulating members 28, one of 105 which is best shown in Fig. 7. Each member is substantially L shaped in form and includes an upright block-like body 29 having a lateral extension at one end, and a recess 30 in the other end. In the extension 110 end of said member and extending part way into the body thereof are grooves or recesses 31 which define spaced plate like parts 32. Said grooves and plate-like parts are so disposed as to provide a plate like part on one 115 side of said member and a groove like part on the other side thereof. The outer end edges 33 of said plate like parts are also finished off at an angle less than a right angle and are inclined downwardly from the rear side of said body toward the end of the extension. The members 28 associated with said bars 17 and 18 are identical but occupy end for end reversed positions with respect to each other so that the ends 120 of the bodies 29 of said members face toward the shoulder bars 21 thus bringing the recesses 22 and 30 respectively into alignment and in which expansion helical springs 34 are interposed to normally urge said 125 130

members away from their associated shoulder members.

When all the members 23 and 28 are in their respective positions the plate parts 26 of the members 23 associated with the cross bar 13 are located in the same plane as the plate parts 32 of the members 28 associated with the cross bar 18, which plane is in the plane of the recesses 25 and 31, respectively, of the members 23 and 28, associated with the cross bars 14 and 17, respectively. Likewise the plate parts 26 of the members 23 associated with the cross bar 14 are located in the same plane as the plate parts 32 of the members 28 associated with the cross bar 17 which is coincident with the planes of the recesses 25 and 31 in the first mentioned members 23 and 28. In "threading" the strands 11 through the manipulating members, alternate strands are disposed between the angular ends 27 and 33 of one set of associated members 23 and 28 and the intermediate strands are disposed between the angular ends 27 and 33 of the other set of associated members 23 and 28 respectively. In the reciprocations of said sets of associated members 23 and 28, the strands are free to follow said plate parts which are movable in the grooves 25 and 31 of the other associated members 23 and 28, as before described. With the ends of the various plate parts "finished off" as before described, at no time will all of said ends be arranged in the same common plane but said ends will overlap one another so that the strand portions are never in a position wherein they may become displaced laterally or pinched or otherwise be engaged by the laterally adjacent plate parts. As alternate strands are moved in one direction the intermediate strands are moved in the opposite direction so as to form a shed into which a stake 35 is inserted and after insertion of one stake said strands receive a reverse movement to lock said stake in place and to form a new shed into which another stake is inserted and so on.

Each associated set of stake manipulating members will, of course, actuate as many strands as there are plate parts to each member and as shown herein as each manipulating member includes three plate parts, three alternate strands are operated upon by one set of manipulating members and three intermediate strands are operated upon by an adjacent set of manipulating members. The number of strands actuated by each set of manipulating members is thus given by way of illustration only and not by way of limitation because as is apparent the members of each set of manipulating members may be made with four or two plate parts to operate upon four or two stakes at a time without departing from the spirit of the invention.

Positive movement toward each other is imparted to the members 23 associated with

the cross bars 13 and 14 in the following manner. Pivotedly connected at one end between the ears 24^a of each member 23 is the rear end of a link 36, the other end of which carries a cross pin 36^a. The cross pin of each link bears in a rearwardly opening slot 37 in vertically disposed posts 38 fixed to the forward edge of the flanges 19 of the front, top and bottom cross members 17 and 18. In each link, midway between its ends is formed a slot 39 and located in said slot is a roller 40 journalled on a stud 41 carried by said link.

42 and 43 indicate top and bottom, transversely extending cylinders fixed on shafts 44 and 45, journalled at their ends in the bridge blocks 7 and side frame members 1 and 2 respectively, said shafts being located in the vertical axes of the bearing studs 41 for the rollers 40. Each cylinder is made up of a plurality of sections 42^a—43^a respectively (see Fig. 10) and in the periphery of each section is formed a plurality of arcuately spaced, longitudinal extending semi-cylindrical grooves or channels 42^b—43^b respectively. The grooves of the various sections of each cylinder align with each other, thus in effect extending from end to end of the respective cylinders. In said grooves or recesses are seated a plurality of cam bars 42^c and 43^c respectively. Said bars are cylindrical in cross section and, of course, portions thereof project beyond the periphery of the associated cylinders so that they may have respective engagement with the rollers 40 to move said rollers away from the associated cylinders and, of course, impart a movement in one direction to the associated manipulating members 23—23. The cam bars are each provided with one or more cut away portions or transverse grooves 42^d—43^d, the bottoms of which are flush with the peripheries of the associated cylinder sections and each cam bar is secured in its associated groove by screws 46 as best shown in Fig. 11. The disposition of said grooves in said cam bar determines the actuation of the stake manipulating member as is apparent and as said cylinders control the disposition of strands for both a plain fabric wherein alternate strands pass over and under the stakes and a fabric embodying certain designs or patterns therein, the arrangement of said recesses in said bars on parts of said cylinders will be different from those on other parts of said cylinders. For instance for a part way about one cylinder the alternate bars will be full and complete throughout the length thereof as the bar A in Fig. 11 and the intermediate bars will have the recesses therein, spaced apart throughout their length, a distance equal to the spacing between the rollers 40 as the bar B in said Fig. 11. Thus in the rotation of the cylinders 42—43 as the full and complete bars A

on both cylinders approach the associated rollers 40, said rollers associated with one cylinder will be moved toward those associated with the other cylinder imparting a reciprocation to the associated manipulating members in the direction of each other so that portions of alternate strands will be shifted through and beyond a neutral plane which is that plane in which the stakes are inserted and portions of the intermediate stakes will be shifted through and beyond said neutral plane in the other direction. This will form a shed into which a stake is inserted and as the bar B approaches the rollers, the recesses being in line with said rollers will permit said rollers to be returned toward said cylinders under the action of the springs 34, thus reversing the positions of the strands and forming another 20 shed into which the next stake is inserted and so on.

It will be noted from Fig. 11 that the next bar C has only one recess therein. The corresponding bar on the other cylinder will have a part of full diameter in line therewith so that as said bar C approaches its set of associated rollers all but one are actuated, thus leaving the associated manipulating member 23 and the strands therein in the position they were left in after passage of the bar B. As the part of full diameter of the corresponding bar on the other cylinder approaches the associated roller, it will actuate the same to move the associated manipulating members to bring the intermediate strands therein into the plane of the strands left undisturbed as before mentioned so that a group of adjacent alternate and intermediate strands are all disposed in a single plane, and will be disposed in this manner upon a stake after its insertion to the shed, as shown at C¹ in Fig. 9. The next bar D will have a plurality of recesses therein but in line with the recess in bar C is a part of full diameter so that a shed is formed for the insertion of a stake wherein a group of strands is disposed on one side of said stake and adjacent groups of stakes are disposed on the other side of said stakes as shown at D¹ in Fig. 9. The successive bars on one cylinder have their recess and parts of full diameter disposed to further carry out the design intended as best shown in Fig. 9, and the bars on the other cylinder has its parts of full diameter to correspond with the recesses of the bars on the first cylinder as is apparent. When the pattern has been completed, the bars are disposed to again produce plain fabric with alternate strands over one stake and under the next and so on.

The bottom cylinder shaft 45 is driven in a step by step manner as will later appear and this step by step movement is imparted to the top cylinder shaft 44 by a suitable 65 chain and sprockets 46 as best shown in Fig.

1. The end of the shaft 45 extending beyond side frame member 1 has a gear 47 fixed thereto and attached to said gear is a ratchet wheel 48. Below and in line with the cylinder shaft 45 is another horizontal transverse shaft 49 to the end of which is fixed a gear 47^a carrying a ratchet 48^a, which gear and ratchet are similar to the gear and ratchet 47 and 48 before mentioned. The gears 47 and 47^a are operatively connected by an idler pinion 50 on a shaft 51 located in the horizontal plane of the drive shaft 12. Loosely mounted on the end of the shaft 45 adjacent the ratchet 48 is a swingable arm 52. Pivoted at 53 to the free end of the swingable arm 52 is a double pawl 54 having oppositely facing pawl members 54^a—54^b as best shown in Fig. 8. The double pawl 54 is so held that the pawl member 54^a may be in engagement with the teeth of the ratchet 48 or it may be so held that the pawl member 54^b is engaged with the teeth of the ratchet 48^a, the holding means comprising a spring 55 fixed at one end to the pawl and at its other end to said arm, said pawl operating on both sides of a center defined by the pivotal connection 53. To the free end of the arm 52 is connected one end of a rod or link 56, the other end of which carries a roller 57. Said last mentioned end of said link is connected to the short arm 58^a of a double arm lever 58 pivoted to the side frame as at 59.

Between and in the plane of the drive shaft 12 and shaft 51 is a shaft 60 to which is fixed just within the side frame member 2 a gear 61 meshing with and driven by a pinion 62 on the drive shaft 12. On the extreme outer end of the shaft without the frame member 2 is fixed a cam 63 upon the periphery of which the roller 57 has rolling engagement as best shown in Fig. 8. As the shaft 60 is rotated it will through the cam and link impart a to and fro swinging movement to the arm 52 and a step by step movement to that ratchet 48—48^a with which the pawl is in contact.

Means is provided in connection with the ratchet wheels 48—48^a to automatically shift the pawl 54 from one ratchet to the other when a complete pattern has been woven so as to immediately repeat the same if so desired and this means is as follows. In each ratchet is provided a plurality of arcuately spaced holes 64—64 into any one of which may be threaded a pin 65—65. In the rotation of that ratchet driven by the pawl, said pin will engage the associated arm (54^a or 54^b) and withdraw said pawl from one ratchet and cause it to engage the other so that the rotation of the cylinders actuating the strand manipulating members are reversed. By setting the pins 65 in the proper holes 64, this reversal may be produced at any desired time and at any point in the 130

weaving of the pattern or design after which that part of the pattern just produced is again produced but in an inverse order.

The stakes 35 are fed into the sheds as they are formed by continuously rotating top and bottom rollers 66 and 67 (see Fig. 12) suitably journaled in the opening 8 associated with the side frame member 1 and geared together. The top roller has a pulley 68 associated therewith and which is driven by a belt 69 from a motor 70 mounted on the bridge block 7 of the side frame member 1 and stakes are delivered to said rollers from a suitable hopper or magazine as will later appear. After the stakes are inserted into the successive sheds as they are formed, the formed fabric passes over the top of a transversely extending horizontal roll 71 with which a second and similar roll 72 is associated, the fabric following about a portion of said roll 71 and then in between both of said rolls and is led off from the bottom of the roll 72 to a winding roll or mandrel at the rear of the machine. The rolls 71 and 72 are fixed on associated shafts 71^a—72^a, respectively, journaled in the side frame members 1 and 2, and secured to said shafts without the frame member 2 are intermeshing gears 71^b—72^b (see Fig. 8). Both of said rolls have longitudinally extending corrugations 71^c—72^c on their peripheries, which corrugations have angularly disposed surfaces as distinguished from the usual undulating surfaces and said surfaces on both rolls are so correlated that when the fabric passes downwardly between them, said surfaces will conform to the contours of both faces of the fabric. Said rolls are rotated step by step in timed relation with the insertion of the stakes into the successive sheds as they are formed and as the fabric passes the common horizontal plane of said rolls, said surfaces coact to more securely "set" the strands upon the stakes. Step by step rotative movement is imparted to said rolls as follows:—Secured to the gear 72^b is a ratchet wheel 73 and loosely mounted on the end of the shaft 72^a adjacent said gear is a swinging arm 73^a (see Fig. 8). Said arm carries a suitable spring pressed dog 74 which is adapted for engagement with the teeth of said ratchet and connected to said arm is one end of a connecting rod 75, the other end of which is connected to the long arm 58^b of the lever 58, before mentioned. It is apparent that as the double arm lever 58 is rocked by the cam 63 a step by step rotative movement is imparted to the roll 72 and by the gears 71^b—72^b to the roll 71 in the opposite direction.

As before mentioned, after the fabric leaves the corrugated rolls 71—72 it passes to a winding roll at the rear end of the machine. 76 indicates said winding roll which

comprises a tubular body 76^a removably mounted in roll ends 77, said tubular body having a longitudinal slot 76^b into which the end of the fabric may be inserted to operatively connect it to said roll so that it may be wound thereupon in the rotation of said roll. The roll ends 77 are fixed to a shaft 78 journaled in suitable bearings formed on rearward extensions 1^a and 2^a of the side frame members 1 and 2, respectively. On that end of the shaft 78 projecting beyond the frame extension 1^a is mounted a friction drive slip clutch 79 operatively driven by a sprocket 80 on said shaft 78, said sprocket being in turn driven by a chain 81 from a similar sprocket 82 fixed on the associated end of the cylinder shaft 72^a. As the construction of the friction slip clutch forms no particular part of the present invention, it is not thought necessary to describe the same in further detail. However, it so operates as to drive the winding roll in a manner accommodating the increasing diameter of fabric as it is wound upon said roll. When a sufficient amount of fabric has been wound upon said roll, the tubular body 76^a may be removed and another substituted in its place.

In connection with the means for inserting stakes into the sheds as they are formed, which means includes the rolls 66 and 67, I provide a means for feeding the stakes one at a time from a magazine or holder in proper timed relation to the formation of said sheds and such means are as follows: Projecting laterally from the end frame member 1, near its forward end is a frame extension 83 (see Figs. 1 and 12). On said frame extension are front and rear, horizontally extending flat plates providing spaced rails 84—84. On said plates toward their outer ends is mounted a magazine or holder 85 in the form of a relatively narrow, high upright box open at its top and at that end facing said frame member 1. A plurality of stakes 35 is placed with their outer ends in bunched relation in said magazine and the forward portions thereof pass between two vertical plates 86 and 87 which are spaced apart a distance to provide a slot 88 equal to substantially the diameter of the stakes employed. Said plates are located nearer the inserting rolls 66—67 than the magazine 85 and are supported from the rails or guides 84 by brackets 85^a. When said stakes are in the magazine with their forward portions positioned in the slot 88, one above the other, they will assume a fan shape-like formation. The extreme forward ends of the stakes engage a guide plate 89 of curved form suitably supported in a substantially vertical position adjacent the frame member 1, said guide plates having laterally spaced guide rods 90 which prevent said extreme ends of the stakes from flexing laterally, thus holding them in the desired

plane. Near the bottom end of said guide plate 89 is formed an opening 91 (see Fig. 12) which is located in the horizontal plane of the peripheral meeting parts of the stake inserting rolls 66-67 which plane is substantially coincident with the plane of the bottom ends of the slot (88) forming plates 86 and 87 respectively.

Means are provided for gripping the bottom-most stake in the slot 88 and for inserting its inner end through the opening 91 into and between the rolls 66-67, and such means are as follows: Slidable on the rails 84-84 between the slot forming plates 86 and 87 and the guide plate 89 is a reciprocating block 92 and pivoted on said block as at 93 is a pair of outwardly extending and normally diverging links 94-94. Said links are pivotally connected to link blocks 95-95 which in turn are pivoted on a common vertical axis 96 mounted on the forward or inner end of a carriage 97 slidable on said rails 84. Said carriage comprises top and bottom plates 98-99, the longitudinal marginal parts of which embrace opposed inner portions of the rails 84 and said plates are secured together by coacting bolts and springs 100 which act to draw said plates together and provide a frictional clamping action on said rails. Each link block 95 carries a gripper jaw 101 and on the inner end of one jaw is secured a transverse bridge or guard plate 102. The top edge of said guard plate terminates short of the plane of the top surface of the jaw block so that when said jaws close they can grip only one stake at a time.

Reciprocating movement is imparted to the block 92 by a connecting rod 103, one end of which is pivoted at 104 to an extension on the bottom of said block and the other end of which is connected to a crank pin 105 on a disc 106 fixed on a horizontal shaft 107 journalled at its ends in the extension frame 83. Said shaft is provided with a sprocket 108 driven by a chain 109 which passes over suitable idler sprockets carried by said extension frame. The chain 109 is in turn driven by a sprocket 109^a on a longitudinal counter shaft 109^b journalled in inwardly extending arms 109^c carried by the side frame member 1. On said shaft is a worm gear 109^a meshing with and driven by a worm 109^f on the shaft 60, all as indicated in dotted lines in Fig. 1. In the rotation of the shaft 107 a reciprocating movement toward the rollers 66-67 will be imparted to the block 92. Said movement of said block is resisted somewhat by the frictional engagement of the carriage 97 with the rails 84 with the result that the inner ends of the links 94-94 are caused to move toward each other, imparting a similar movement to the inner ends of the jaw blocks 95. As said jaw blocks carry the

gripping jaws 101, said jaws will grip that stake resting on the guard plate 102 and in the further forward movement of said block 92 will overcome the frictional resistance of the carriage 97 so that said stake is fed through the opening 91 in the guard plate 90 into and between the rolls 66-67 to be inserted thereby into the shed formed by the strands, as before mentioned. In the rearward reciprocation of the block 92, the links 94 and jaw blocks 95 will open up due to the resistance offered by the carriage 97 and in the further movement of said block, the resistance of the carriage is overcome so that all parts are returned to their normal starting position.

In the forward movement of the block 92, means are provided to engage the stakes near the bottom end of the slot 88 between the plates 86-87 so that no more than a single stake is engaged by the jaws 101-101 and fed to the rolls 66-67. Said means includes a bell crank lever 110 which is pivoted to the plate 86 as at 111. The vertical arm 110^a of said lever is adapted to swing toward and away from the slot 88 and is so formed as to normally engage the next to the bottom stake in said slot so that it cannot descend in the outward withdrawal of the bottom-most stake. The horizontal arm 110^b of said lever projects laterally beyond the plate 86 where it is connected by links 112 with the front end of a lever 113. Said lever 113 is located below the rearmost rail 84 which carries a depending bracket 114 to which the other end of the lever 113 is pivoted. The free end of said lever which is rounded off normally engages upon a roller 115 coincident with the connection 104 between the block 92 and connecting rod 103. A spring 116 which is connected at one end to a part of the machine frame and at its other end is connected to said lever, normally urges said lever into engagement with the roller 115. However, when said block 92 is moved towards the rollers 66-67 as before described the lever 113 is left unsupported so that it moves downwardly, thus rocking the bell crank lever 110, the vertical arm of which will act on the stakes as before mentioned. In the reverse movement of the block 92, the roller 115 will again engage the free end of the lever 113 and will move it upwardly against the action of the spring 116 when the vertical arm of the bell crank lever 110 will swing away from the slot 88 under the action of a spring 117 connecting the horizontal arm of the bell crank lever 110 with the plate 86 so that the now bottom-most stake is presented to the gripper jaws 101, the link 112 being made in two parts to provide enough latitude in movement.

In many instances the stakes are not perfectly straight but are slightly bent and if inserted into the shed in its bent condition,

- it is apparent that an irregular fabric will result. To overcome such a condition I provide means to straighten the stakes after incorporation into the fabric and such means are as follows: 120 indicates a transversely extending shaft (see Fig. 2) journaled at its ends in brackets 121 fixed to the inner surfaces of the rear upright standards 6—6. Loosely mounted on said shaft 5 for independent rocking movement is a plurality of laterally spaced bell crank shaped, straightening plates 122 having a stake engaging arm 123 and a gravity arm 124. The gravity arms of all straightening plates depend into the plane of the horizontal flange 10 of the cross bar 14 and abut against an angle bar 125 located adjacent said flange. Said angle bar has ears 125^a near its ends which receive the two ends of swingable arms 126, 15 the bottom ends of which are journaled on a cross rod 127 supported at its ends in the side frame members 1 and 2, thus permitting a short swinging movement of said angle bar toward and away from said horizontal flange of the cross member 14. Swinging 20 movement of said angle bar away from the cross member 14 is provided by a pair of levers 128, one located near each side frame member and pivoted thereto as at 129. The 25 top arm 128^a of each lever is pivotally connected to the associated end of angle bar 125 as at 130 and the bottom arm 128^b of each lever carries a roller 131 adapted to be engaged by a cam 132 carried on that face of 30 the associated gear 61 adjacent the side frame members 1 and 2.
- In the step by step forward movement of the fabric and in the formation of a new shed, the previously inserted stake is moved 35 toward the stake engaging arms 123 some of which stand in planes to enter those spaces between adjacent strands, provided by the intermediate strands as they pass over the stake. Such arms are in the nature of 40 aligned abutments against which the stakes are drawn in the movement of the fabric to straighten the stakes. At the proper time, the cams 132 actuate the levers 128 to move the angle bar 125 away from the horizontal 45 flange of the cross member 14 and thus through the gravity arms of said plates swing the stake engaging arms thereof downwardly and away from the stake so that said stake may freely pass the same in the movement of the preformed fabric. The angle 50 bar 125 is then moved toward the cross member 14 by springs 133 acting through the levers 128, when the gravity arms will swing the stake engaging arms into position so that 55 some of them will engage the next approaching stake. Thus as it is apparent that the straightening plates are capable of an independent movement away from the angle bar as when certain of the stake engaging 60 arms thereof engage with strand portions 65 under the stake. However, by employing a sufficient number of said plates, enough of them will always find their way into a position to be engaged by the stake while the others will idly work so that those strand portions under the stake and in line with said other plates will rock or "float" and thus in no manner interfere with the movement of the preformed fabric. 70
- As the operation of the parts as well as their arrangement and construction have been described, it is not thought necessary to again set forth said operation because the same will be apparent to those familiar with the art. 75
- The machine produces plain fabric as well as fabric with designs or configurations therein and said designs may be repeated or reversed as desired. 80
- While in describing my invention, I have referred to certain details of mechanical construction as well as form and arrangement of parts, I do not wish to be limited thereto except as may be pointed out in the appended claims. 85
- I claim as my invention:
1. A reed weaving machine embodying therein, sets of top and bottom strand manipulating members adapted to engage portions of alternate and intermediate strands respectively and to move them from one side to the other and vice versa of a neutral plane to form successive sheds, a cylinder disposed above and associated with the top strand manipulating members and a second cylinder disposed below and associated with the bottom strand manipulating members, said cylinders each having such a contour as to impart movement to all of its associated manipulating members for a predetermined time, and less than all of said members at another time to form a shed wherein adjacent alternate and intermediate strands are in the same common plane, and means for inserting stakes into said sheds. 90
  2. A reed weaving machine embodying therein, set of top and bottom strand manipulating members adapted to engage portions of alternate and intermediate strands respectively and to move them from one side to the other and vice versa of a neutral plane to form successive sheds, rotary members, one positioned above and one positioned below and associated with each set of manipulating members for imparting a reciprocating movement to all of the members of the associated set for a part of a revolution and for imparting a reciprocating movement to less than all of the members of said set for another part of a revolution to 105 form a shed wherein adjacent alternate and intermediate strands are in the same common plane, and means for inserting stakes into said sheds. 110
  3. A reed weaving machine embodying 115

therein, sets of top and bottom strand manipulating members adapted to engage portions of alternate and intermediate strands, respectively and to move them from one side to the other and vice versa of a neutral plane to form successive sheds, a rotary pattern controlling member associated with each set of manipulating members, one located above and the other below its associated set of manipulating members, said pattern controlling members each having projections thereon so disposed that in one part of the rotation of said controlling member all of the manipulating members of the associated set are reciprocated and in another part of the rotation less than all are reciprocated to form a shed wherein a number of adjacent alternate and intermediate strands are in the same common plane, and means for inserting stakes into said sheds.

4. A reed weaving machine embodying therein, sets of top and bottom strand manipulating members adapted to engage portions of alternate and intermediate strands, respectively and to move them from one side to the other and vice versa of a neutral plane to form successive sheds, a rotary cylinder associated with each set of manipulating members and one being positioned above and the other below said associated set of manipulating members, means providing areately and longitudinally spaced projections on said cylinder operating in one part of the rotation of the cylinder to reciprocate all of the members of one set and in another part of the rotation thereof to reciprocate less than all of the members of one set to form a shed wherein a number of adjacent and intermediate strands are in the same common plane, and means for inserting stakes into said sheds.

5. A reed weaving machine embodying therein, sets of top and bottom strands manipulating members adapted to engage portions of alternate and intermediate strands, respectively and to move them from one side to the other and vice versa of a neutral plane to form successive sheds, a rotary pattern controlling cylinder associated with each set of manipulating members and one positioned above and the other below its associated set of manipulating members, said cylinders each having a plurality of longitudinal grooves therein, bars having longitudinal projections thereon, seated in each groove, said projections being so disposed that in one part of the rotation of said cylinder all of the manipulating members of one set are reciprocated to form a shed wherein a number of adjacent alternate and intermediate strands are in the same common plane, and means for inserting stakes into said sheds.

6. A reed weaving machine embodying therein a plurality of pairs of opposed strand manipulating devices, each pair

adapted to engage alternate and intermediate strands, respectively, the members of one pair having parts adapted to engage between parts of the members of an opposed pair, means providing a sliding guiding bearing for said pairs of opposed strand manipulating members, power transmitting arms operatively connected to one of the members of each pair, a rotating cylinder associated with each set of manipulating members to impart movement to the associated power transmitting arms thereof to form a shed and spring means operatively engaged between the other member of each pair and a fixed part of said sliding bearing providing means to form another shed and means for inserting stakes into said sheds.

7. A reed weaving machine embodying therein, sets of oppositely reciprocating strand manipulating members adapted to engage portions of alternate and intermediate strands, respectively, and to move them from one side to the other of a neutral plane to form successive sheds, means for inserting stakes into said sheds, step by step rotating cylinders adapted to control the action of said manipulating members in the forming of the sheds so that at times all the alternate and intermediate strands are disposed upon the opposite sides of adjacent stakes and at other times some of the adjacent and intermediate strands are disposed on the same side of one stake, and means for reversing the rotation of said cylinders.

8. A reed weaving machine embodying therein oppositely reciprocating sets of strand manipulating members, step by step rotating cylinders for actuating said manipulating members, means driving one cylinder from the other, means for imparting a step by step rotating movement to one cylinder, and means for reversing the rotation of said last mentioned cylinder.

9. A reed weaving machine embodying therein oppositely reciprocating sets of strand manipulating members, step by step rotating cylinders for actuating said manipulating members, means driving one cylinder from the other, means for imparting a step by step rotating movement to one cylinder, and means operating automatically to reverse the rotation of said cylinder at desired intervals.

10. A reed weaving machine embodying therein oppositely reciprocating sets of strand manipulating members, step by step rotating cylinders for actuating said manipulating members, means driving one cylinder from the other, means for imparting a step by step rotating movement to one cylinder, a ratchet wheel operatively connected to one cylinder for rotating the same in one direction, a second ratchet wheel operatively connected to said cylinder for ro-

- tating it in the opposite direction, a swinging arm and a pawl actuated thereby and adapted to be engaged with either ratchet wheel.
5. 11. A reed weaving machine embodying therein oppositely reciprocating sets of strand manipulating members, step by step rotating cylinders for actuating said manipulating members, means driving one cylinder from the other, means for imparting a step by step rotating movement to one cylinder, a ratchet wheel operatively connected to one cylinder for rotating the same in one direction, a second ratchet wheel operatively connected to said cylinder for rotating it in the opposite direction, a swinging arm pivoted coincident with the axis of said cylinder, and a double pawl carried thereby and adapted to be engaged with either ratchet wheel.
10. 12. A reed weaving machine embodying therein oppositely reciprocating sets of strand manipulating members, step by step rotating cylinders for actuating said manipulating members, means driving one cylinder from the other, means for imparting a step by step rotating movement to one cylinder, a ratchet wheel operatively connected to one cylinder for rotating the same in one direction, a second ratchet wheel operatively connected to said cylinder for rotating it in the opposite direction, a swinging arm pivoted coincident with the axis of said cylinder, and a double pawl carried by said swinging arm and means carried by said ratchet wheels for moving the pawl from engagement with one ratchet into engagement with the other.
15. 13. A reed weaving machine embodying therein means for forming adjacent alternate and intermediate strands into successive sheds, means for inserting stakes into said sheds as they are formed, means for forwarding the fabric as it is formed, and means providing aligned abutments against which the stakes engage in the forward movement of the fabric for straightening the same.
20. 14. A reed weaving machine embodying therein means for forming adjacent alternate and intermediate strands into successive sheds, means for inserting stakes into said sheds as they are formed, means for forwarding the fabric as it is formed, means
25. providing pivotally mounted abutments some of which engage one stake in the forward movement of the fabric for straightening the stake and others of which engage the next stake in the forward movement of the fabric for straightening said stake, and means for moving said abutments away from the straightened stakes.
30. 15. A reed weaving machine embodying therein means for forming adjacent alternate and intermediate strands into successive sheds, means for inserting stakes into said sheds as they are formed, means for forwarding the fabric as it is formed, means providing a plurality of stake straightening plates arranged parallel with the strands, and means providing a pivotal axis for said plates so that certain of said plates will swing by gravity to bring portions thereof into position to be engaged by the stakes in the forward movement of the fabric.
35. 16. A reed weaving machine embodying therein means for forming adjacent alternate and intermediate strands into successive sheds, means for inserting stakes into said sheds as they are formed, means for forwarding the fabric as it is formed, plate members extending parallel with said strands, means providing a pivotal axis upon which said plates may swing independently of each other, said plates each including a stake engaging arm and a weighted arm for yielding and holding the stake engaging arm in a position to be engaged by the stakes to straighten the same in the forward movement of the fabric.
40. 17. A reed weaving machine embodying therein, means for forming adjacent alternate and intermediate strands into successive sheds, means for inserting stakes into said sheds as they are formed, plate members each including a stake engaging arm and a weighted arm, means providing a pivotal axis upon which said plates may swing independently, the weighted arm of each plate yieldingly holding the stake engaging arm in a position to be engaged by the stakes in the forward movement of the fabric, and means acting simultaneously on all of said weighted arms to swing the other arms out of engagement with said stakes.
45. In testimony whereof, I have hereunto set my hand, this 8th day of September, 1925.
- MARSHALL B. LLOYD.
